T. P. ARCHER

LOCK BOLT

Filed July 30, 1924

UNITED STATES PATENT OFFICE.

THOMAS P. ARCHER, OF DETROIT, MICHIGAN, ASSIGNOR TO TERNSTEDT MANUFACTURING COMPANY, OF DETROIT, MICHIGAN, A CORPORATION OF MICHIGAN.

LOCK BOLT.

Application filed July 30, 1924. Serial No. 729,029.

To all whom it may concern:

Be it known that I, THOMAS P. ARCHER, a citizen of the United States, residing at Detroit, in the county of Wayne and State of Michigan, have invented certain new and useful Improvements in Lock Bolts, of which the following is a specification.

This invention has for its object an improvement in the structure of a sliding lock bolt. It is the object of the invention to get the cost of an ordinary coach lock bolt down to a minimum and at the same time provide a latch bolt which has all the characteristics regarding functions and efficiency which attends those of more expensive design.

In the drawings:

Fig. 1 is a view of a vertical spindle coach lock with the cover plate removed.

Fig. 2 is a perspective of the sliding latch bolt.

Fig. 3 is a fragmentary view of the sliding latch bolt used with the ordinary coach lock.

Up to a few years ago it has been customary in the production of locks to make a sliding bolt member in the form of a casting provided with the necessary head, projections, and curves. More recently the bolt heads and the bolt body have been made separate and secured together. In this way the bolt head can be cut from rolled stock and the body of the bolt can be a stamping. However, it has been found necessary to form the roll back abutment as some special stamping and clamp the same to the body of the bolt by projecting lugs, fingers or otherwise. This kind of construction requires somewhat expensive dies and a number of stamping and punching operations. Operations of this kind may seem simple but when figured up the cost sheets of the manufacturer involve a considerable outlay in providing the necessary roll back abutment in a stamped sliding bolt.

It is the object of the present invention to afford a design of bolt which is very much cheaper and affords just as good a roll back abutment. To this end the bolt is divided in the bolt head *a*, which is preferably a piece of cut roll stock and the stamped bolt body *b*. Instead of making the bolt body out of a single piece as is ordinarily the case, the bolt body is made up of two separate stampings which are simply folded up to form right angles. The rear of the forward bolt body section is folded up to form the angle *c* while the short rear bolt body section is folded up to form the angle *d*. The perpendicular portions of these members are lapped together and spot-welded. This forms a suitable abutment for the crank type of roll back *e* used with a vertical spindle lock or the lever type inside retractor designated *f*.

The rear angle piece of the sliding bolt is necessary as a guide for the bolt. Here it is shown as guided from the struck up lugs *g* of the front plate *h* of the lock.

What I claim is:

1. A bolt comprising a body portion made of two pieces having their meeting portions turned up into angle plates which are secured together to form the roll back abutment.

2. A sliding bolt having a body portion made of two portions that are aligned but which are turned up into right angular plates where they meet and are welded together to form the roll back abutment.

3. A sliding bolt, having a stamped metal body portion having the rear end turned up perpendicularly, a second rear portion formed up into an angle and lapped against the turned up portion of the first-mentioned body member and secured thereto to form the roll back abutment.

In testimony whereof I have affixed my signature.

THOMAS P. ARCHER.
